(57) **CLAIM**

The ornamental design for a cooking tenderizer, as shown and described.

DESCRIPTION

FIG. 1 is a top front left view for a cooking tenderizer shown in an environment of use showing my new design;
 FIG. 2 is a top front left view shown in an environment of use thereof;

FIG. 3 is a top front left view thereof;

FIG. 4 is a left side view thereof;

FIG. 5 is a right side view thereof;

FIG. 6 is a front side view thereof;

FIG. 7 is a back side view thereof;

FIG. 8 is a top side view thereof; and,

FIG. 9 is a bottom side view thereof.

The evenly dashed broken lines show portions of the cooking tenderizer form no part of the claimed design.
